FIG.1.

FIG.2.

LAWRENCE E. BLAZEY
INVENTOR.

BY *J. Russell Jeter*

ATTORNEY.

UNITED STATES PATENT OFFICE

125,064

DESIGN FOR A DRAFTING MACHINE PROTRACTOR HEAD

Lawrence E. Blazey, Cleveland, Ohio, assignor to
Keuffel & Esser Company, Hoboken, N. J., a
corporation of New Jersey

Application May 16, 1940, Serial No. 92,412

Term of patent 14 years

To all whom it may concern:

Be it known that I, Lawrence E. Blazey, a citizen of the United States and residing in the town of Cleveland, county of Cuyahoga and State of Ohio, have invented a new, original, and ornamental Design for Drafting Machine Protractor Head, of which the following is a specification, reference being had to the accompanying drawing, forming a part thereof.

Figure 1 is an isometric view showing the drafting machine protractor head.

Figure 2 is a view in side elevation of the drafting machine protractor head.

I claim:

The ornamental design for a drafting machine protractor head, as shown.

LAWRENCE E. BLAZEY.
